UNITED STATES PATENT OFFICE.

CALLO FAHRNEY, OF POLO, ILLINOIS.

ROAD-CART.

SPECIFICATION forming part of Letters Patent No. 431,569, dated July 8, 1890.

Application filed March 12, 1890. Serial No. 343,579. (No model.)

To all whom it may concern:

Be it known that I, CALLO FAHRNEY, a citizen of the United States, residing at Polo, in the county of Ogle and State of Illinois, have 5 invented certain new and useful Improvements in Road-Carts; and I do declare the following to be a full, clear, and exact description of the invention, such as will enable others skilled in the art to which it appertains to 10 make and use the same, reference being had to the accompanying drawings, and to the letters and figures of reference marked thereon, which form a part of this specification.

My invention relates to improvements in 15 that class of road-carts in which the body of the vehicle is supported on suitable springs from the thills; and the objects of my improvements are, first, to interpose between the front end of said body and the cross-bar 20 which unites the thills a medium of connection rigidly affixed at one end to said bar and at the other to said body, and yet affording in itself the necessary and sufficient flexibility 25 or elasticity in all directions to prevent the jar or oscillation of said cross-bar from being imparted to the body of the vehicle. If the connection of the body at its front end to the thills or cross-bar has no elasticity, the jar or 30 oscillation of the latter parts will be communicated to the foot-board portion of the body of the vehicle in successive concussions, while if said connection is an articulated one of any description it produces an unpleasant clatter or rattle. The object of my improvement 35 is, therefore, in this department to avoid the noise of an articulated connection by making the attachments of my intermediate connection rigid at all points, and to avoid imparting pulsations from the cross-bar to the 40 body by making said intermediate connection inherently of an elastic character and form, and therefore flexible in every direction.

Second. The object of my improvement is 45 to afford means of changing the angle of the occupant's seat with reference to the parts supporting the same. With the seat of a road-cart in one fixed relation to the residue of the latter the use of horses of a different

height, by changing the altitude of the thills, 50 varies the plane of the seat forward and back. Again, two persons occupying the seat will necessarily depress the springs more than one occupant, and such increased depression also changes the angle of said seat. 55

The purpose of the second part of my invention is to adjust the position or plane of the occupant's seat to the variant altitudes of the thills or to the amount of pressure 60 upon said springs. 65

I attain these objects by the mechanism illustrated in the accompanying drawings, in which—

Figure 1 is a partial side elevation of a cart embodying my improvements. Fig. 2 is a 65 front view of the attachment of the intermediate attachment H to the cross-bar connecting the thills. Fig. 3 is a view of the under side of part of the vehicle and of said bar and attachment of said connection thereto. 70 Fig. 4 is a vertical view of the seat-adjusting devices.

As my invention is adapted to be used in most of the well-known forms of carts and pertains only to the two departments named, 75 I do not deem it essential to show or describe the vehicle any farther than will render intelligible the location and operation of my improvements.

Referring to the first part of my invention, 80 A A are the thills, supported in the usual mode upon the axle B.

C is a cross-bar connecting the thills A at the front end of the body of the vehicle, and to which the draft is applied. 85

D is the body of the vehicle, consisting of the seat E and foot-board F, integral with each other and supported from the thills A upon suitable springs G at about the arch of said thills. 90

H is the means of interconnection of the foot-board F and cross-bar C, and consists of a steel spring provided with a central loop 1, which is placed centrally under the bar C, with said loop projecting forward and lying 95 parallel with and against the under side of said bar, and rigidly attached thereto by vertical hooks or eyebolts 2 2, which embrace

said spring at its lower end and pass up through the bar C, and are fastened upon the upper surface of the latter by ordinary nuts 3. By this means the spring H is held tightly 5 at its central portion against the bar C, and by means of the loop 1 being held against the plane of the lower side of said bar is prevented from turning. The portion of the spring H between the bolts 2 is held rigidly 10 against said bar from both lateral oscillation or casual rotation, and is consequently noiseless. The space between the bolts 2 is about four inches, and the spring H is about twenty-six inches in its entire width. From about 15 an inch outside of each bolt 2 the part 4 of said spring H is bent downward from the bar C to the point where said spring is bent backward. (See Fig. 2.) The ends 6 of said spring, which extend backward in line with the ve- 20 hicle, are about six inches in length, and are fastened, respectively, to the foot-board F by an eyebolt 7, through which the end of the spring is passed, and by bolts 8, which attach said spring at its ends to the foot-board 25 F. This junction of the ends 6 of the spring H with the foot-board is rigid and tight, so as to permit no oscillation or rattling. The elasticity of the spring H inheres in both ends thereof from the point near the bolts 2, where 30 the contact with the cross-bar C ceases. The parts 4 of the spring H permit the necessary lateral oscillation, and the parts 4, together with parts 6, permit the necessary vertical movement, so that the jar or concussion of 35 the bar C is exhausted in the spring H before reaching the foot-board F. There is also sufficient longitudinal movement of the bar C obviated or exhausted by the spring H to prevent what is termed "horse motion" from be- 40 ing communicated to the foot-board F or body D. In fact, the torsional character of the spring H is such that, together with the vertical elasticity of the parts 4, the connection of the foot-board F to the cross-bar C is elas- 45 tic and flexible in every direction, while at the same time both the front and rear attachments of said spring are rigid.

Referring to Fig. 1, J is the occupant's seat, which is pivoted about centrally on the seat- 50 standard K by means of a transverse bolt passed transversely through the upper end of the standard K and the cleat L, which supports the seat J. Near the front end of the cleat L is pivotally attached the upper end 55 of a depending rod M, which is held adjustably near its lower end against the seat-standard by a hook bolt 10, the front end of which embraces the rod M, and the shank of which extends through the seat-standard K, and is 60 provided at its rear end with the thumb-nut 11, and by the loosening and tightening of the bolt 10 the rod M can be adjusted vertically and held rigidly, as may be required. Inasmuch as the pivot 9 is about under the 65 center of gravity of the seat J when occupied, but little strain is exerted upon the rod

M, and the latter is therefore easily held in position.

By the adjustment of the seat J described the latter can be set at the proper angle for 70 comfort in reference to the weight to be carried upon the seat, so that the greater depression of the entire seat caused by two occupants, or one heavy person, will not give the seat J a backward and uncomfortable inclination, and said seat J can also be adjusted to the proper position with reference to the height of horses employed. In addition to the noiseless, rigid, and elastic character of the front connection heretofore mentioned, 80 an advantage in the use of spring H consists in the fact that while the springs G, which support the body D, are of sufficient strength to carry two persons, when there is but one occupant of the vehicle he can sit at one end 85 of the seat J and be carried almost wholly upon one of said supporting-springs G, the spring H permitting this without a resulting twist to the body D.

I am aware that vehicle-seats have heretofore been pivoted adjustably at one end; but my central pivoting of the seat requires less movement of the adjusting devices to effect the desired change, and involves substantially no weight of the occupant upon said 95 devices.

What I claim as my invention, and desire to secure by Letters Patent of the United States, is—

1. The spring H, provided with the central 100 loop 1, lateral depending portions 4, and rearward extensions 6, and adapted to be rigidly connected centrally to the cross-bar C or its equivalent, and rigidly connected at its extremities 6 to the front end of the body D, 105 substantially as shown, and for the purpose described.

2. The combination of the cross-bar C, the spring H, provided with central loop 1, rigidly attached to said bar and with the lateral 110 extensions 4, and rear extensions 6, and the body D, rigidly attached to said extremities 6, substantially as shown, and for the purpose described.

3. The combination of the spring H, pro- 115 vided with central loop 1, lateral extensions 4, and rear extensions 6, the cross-bar C, vertical bolts 3, body D, and attachments 8 and 7, substantially as shown, and for the purpose described.

4. The combination of the thills A A, suitably supported at their rear ends upon the axle B, the cross-bar C, the body D, suitably supported about centrally from said thills, and the spring H, rigidly attached centrally to 125 said cross-bar C and extended outwardly and rearwardly from said central attachment, and rigidly attached at its extremities to the body D, substantially as shown, and for the purpose described.

5. The combination of the seat-standard K, 130 seat J, pivotally attached centrally to the up-

per end of said standard, the rod M, pivotally connected at its upper end to the front end of said seat, and the bolt 10, seated in said standard and provided with thumb-screw 11, and adapted to adjustably hold said rod against said standard, substantially as shown, and for the purpose described.

In testimony whereof I affix my signature in presence of two witnesses.

CALLO FAHRNEY.
